2,344,361

Apparatus for forming a bit for a rock drill, comprising a pair of blocks, each having a raised portion on one end, a number of steps on the inner end of which are angularly positioned with respect to the center line of the blocks, and a longitudinal edge rounded on the inner end of the blocks, and a holding frame or box having parallel sides of corresponding length to the blocks, two parallel slots cut in the said base adjacent the closed end of the box and the inner ends of the said slots bevelled inward toward the top and angularly disposed with respect to the center line in correspondence to the steps of the raised portions on the faces of the former blocks, a tongue formed between the slots forming means to bring the blocks into working position in the frame, the end closed and the center of the upper edge lowered as shown at 23 to permit the bit shank being placed in blocks.

UNITED STATES PATENT OFFICE

2,344,361

BIT FORMER

Harold Edward McKeen, Sheep Creek, British Columbia, Canada

Application March 24, 1942, Serial No. 436,055

3 Claims.

(Cl. 76—95)

This invention relates to new and useful improvements in a bit former, its primary object being to provide means whereby rock drill bits may be formed. Said means including a pair of interchangeable blocks which may be refaced, renewed or repaired when damaged or worn in use.

A further object of the invention is to provide a holding frame or box for the said blocks wherein the same are retained in position while the bit is formed thereon.

A still further object is to devise spring means to grip the said blocks and hold the same in spaced apart relation to each other in the box, said spring means being attached to said box.

Another object of the invention is to construct a former comprising a plurality of blocks having more than one face and designed to be rearranged to present another working face when necessary thus increasing the life of the device.

With these and other objects in view that may appear while the description proceeds the invention consists in the novel construction and arrangement of parts as hereinafter more specifically set forth, claimed and shown in the accompanying drawing forming part of this application and in which—

Fig. 1 is a perspective view of my invention.

Fig. 2 is a plan view of the same.

Fig. 3 is a plan view of the holding frame or box showing the spring retaining means therein.

Fig. 4 is a side elevation of one of the former blocks.

Fig. 5 is a plan view of the same showing a modification in the construction of the face.

Referring more in detail to the drawing in which similar reference characters designate corresponding parts throughout the several views it will be seen the invention consists of a pair of former blocks 10 one of which is a right and the other a left hand.

The blocks are of symmetrical design and arranged so that either face may be used thus permitting reversing the same when one face becomes worn or damaged. The working face 11 of the blocks is provided with a raised portion 12 on one end thereof on the inner end of which are a number of steps 13. It will be seen that the steps are angularly positioned with respect to the center line of the blocks. The angle to which these steps are constructed will correspond to the angle of the working edge of the bit 14, shown dotted in Fig. 2. The inner longitudinal edge 15 of the blocks is rounded as shown to accommodate and form the shank of the bit.

In the alternative view shown in Fig. 5, the

steps 13 are shown converging toward the center and both the edges 15 are rounded as shown. With this type of block an additional face is provided thus adding to the economic life of the block.

The holding frame or box 16 comprises a base 17 having parallel sides 18 of corresponding length to the blocks. Two parallel slots 19 are cut in the said base adjacent the closed end of the box and the inner ends 20 of the said slots are bevelled inward toward the top and angularly disposed with respect to the center line in correspondence to the steps of the raised portions 12 on the faces of the former blocks 10. A tongue 21 is formed between the slots forming means to bring the blocks into working position in the frame. The end 22 is closed and the center of the upper edge is lowered as shown at 23 to permit the bit shank 14 being placed in blocks 10.

It will be seen in Fig. 4, where the frame is shown in a dotted line that the slots are designed to receive the said raised portions 12 of the former blocks thereby positioning the blocks in spaced parallel relation to receive the bit to be sharpened therebetween.

The spring retaining means for the blocks consists of a U-shaped spring 24 having its outer ends 25 turned inwards at an angle with respect to the centerline thereof. The spring is secured centrally to the end 22 of the frame by a bolt or rivet 26. The spring arms 27 are arranged to normally diverge from the center so that the tension thereof will hold the blocks securely against the side walls 18 of the frame thus preventing inadvertent movement of the blocks when in use.

In operation, the bit former die assembly shown in Fig. 1 is mounted in the sharpening machine with a complementary bit forming die mounted thereabove and movable towards the first die assembly whereby a bit placed between the die assemblies will be forged into the proper shape. An air hammer or other hammering device actuates the movable die assembly to produce the desired force to hammer the bit between the forming blocks until it is properly shaped. The bit to be sharpened is first heated to the proper temperature and is then placed centrally of the former blocks with the shank resting in the recess 23 of the closed end of the holding box. The working edges of the bit wings rest on the steps 13, as shown in dotted lines in Fig. 2, and under the hammer action of the movable die assembly the working edges are forged into proper shape.

It is believed that the construction and advan-

ages of the structure shown may be apparent from the foregoing paragraphs taken in conjunction with the accompanying drawing without further detailed description.

While the preferred embodiment of the invention has been disclosed it is understood that minor changes in the details of construction, combination and arrangement of co-operating parts may be resorted to within the scope of what is claimed without departing from the spirit of the invention.

I claim:

1. In a bit former die the combination of a holding frame having spaced parallel slots in its bottom wall at one end, a pair of former blocks adapted to fit in said frame having raised portions on their upper and lower faces at opposite ends, the raised portions on the lower faces being adapted to seat in the slots in the bottom of said frame whereby the former blocks are held in spaced parallel relation, said raised portions having a series of steps at their inner ends to receive the working edge of the bit when placed on the upper faces of the former blocks.
2. In a bit former die the combination of a holding frame having spaced parallel slots in the

bottom wall thereof at one end, a pair of former blocks having raised portions on their upper and lower faces at opposite ends, the inner ends of the raised portions being serrated to receive the working edge of the bit wings, said former blocks being adapted to fit in said frame with the raised portions on the lower faces seated in the slots of the bottom wall, and an expansible spring disposed between said former blocks for holding the blocks in spaced relation.

3. In a bit former die, the combination of a holding frame having spaced parallel slots in the bottom wall thereof at one end, a pair of former blocks having raised portions on their upper and lower faces at opposite ends, the inner ends of the raised portions being serrated to receive the working edge of the bit wings, said former blocks being adapted to fit in said frame with the raised portions on the lower faces seated in the slots of the bottom wall, and a U-shaped spring attached to one end of said frame having diverging arms in contacting engagement with the inner sides of said blocks adapted to exert an outward force on said blocks to hold them in spaced parallel relation.

25 HAROLD EDWARD McKEEN.
